UNITED STATES PATENT OFFICE.

GEORGE W. KERR, OF RACINE, WISCONSIN.

DESIGN FOR A RADIATOR-HOOD FOR AUTOMOBILES.

53,714.

Specification for Design.

Patented Aug. 19, 1919.

Application filed May 2, 1919. Serial No. 294,331. Term of patent 7 years.

To all whom it may concern:

Be it known that I, GEORGE W. KERR, a citizen of the United States, residing at Racine, in the county of Racine and State of Wisconsin, have invented a new, original, and ornamental Design for Radiator-Hoods for Automobiles, of which the following is a specification, reference being had to the accompanying drawing, forming part thereof.

Figure 1 is a plan view of a radiator hood, showing my new design;

Fig. 2 is a front view thereof; and,
Fig. 3 is a side view thereof.

I claim:

The ornamental design for a radiator hood for automobiles as shown.

GEORGE W. KERR.
